UNITED STATES PATENT OFFICE.

HOMER A. PARRISH, OF KALAMAZOO, MICHIGAN, ASSIGNOR OF ONE-TENTH TO
G. EDWIN DUNBAR, OF KALAMAZOO, MICHIGAN.

RELAY.

1,120,846.

Specification of Letters Patent. Patented Dec. 15, 1914.

Application filed December 17, 1913. Serial No. 807,323.

To all whom it may concern:

Be it known that I, HOMER A. PARRISH, a citizen of the United States, residing at Kalamazoo, in the county of Kalamazoo and State of Michigan, have invented certain new and useful Improvements in Relays, of which the following is a specification.

This invention relates to improvements in relays.

The object of this invention is to provide an improved relay which is quickly and positively operated by a normally closed circuit.

Further objects, and objects relating to details and economies of construction and operation will readily appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing forming a part of this specification, in which:

Figure I is a front elevation of my improved relay, the front of the casing being removed. Fig. II is a longitudinal sectional view on the line 4—4 of Fig. I.

In the drawings similar reference characters refer to similar parts throughout the several views and the sectional views are taken looking in the direction of the little arrows at the ends of the section lines.

Considering the numbered parts of the drawing 25 is the casing of the automatic relay, and to the side wall of said casing the solenoids 26 are secured as at 27. The wire 23 is connected to the solenoids 26 and enters the casing through the binding post 24.

From the other end of the solenoid 26 wire 28 leads to a binding post 29.

31 is the armature of the solenoid 26, and is pivoted on the pin 32 secured in the L-shaped bracket 33 which is fastened to the side wall of the casing, as at 34. This armature is held resiliently out of contact with

the solenoid by means of the spring 35 secured at one end of the armature and at the other end to a bracket 36 which is attached to the side wall of the casing as at 37.

38 is a pin which serves as a stop to limit the forward movement of the armature.

Bracket 42 is secured to the side wall of the casing at 43 and carries pin 41, on which the bell crank pawl 39 is pivoted. One arm of said pawl extends downwardly so as to be engaged by the armature 31 when it is drawn forward. The opposite end of this pawl is provided with a notch 49 in the end thereof and a beveled edge 40 so that it may easily be lifted by the contact plate 44.

43 is a spring secured to the pawl 39 and engaging the bracket 42 so as to hold the pawl normally in engaging position.

Bracket 46 is secured to the side wall of the casing at 47 and has an upwardly extending portion on which the notch 49 in the end of the pawl 39 rests. The contact plate 44 is pivoted to this bracket on the pin 45 secured thereto. A small pad of hard rubber 48 is secured to the bracket and serves as a buffer to lessen the jar and noise when the contact plate is forced against the bracket. Contact pin 50 is secured in a post 51 which is mounted on the side wall of the casing. This pin is adjustable by means of the thumb nut 52. Wire 53 is connected to the contact plate 44 through binding post 55. The contact pin 50 is electrically connected with wire 57 through binding post 58. It will readily be seen that when the armature 31 is pulled forward the pawl 39 will be lifted so as to allow the contact plate 44 to drop into contact with pin 50 and close the circuit between wires 57 and 53.

To the side wall of the casing, solenoids 65 are secured at 66. These solenoids are provided with an armature 67 which is pivoted at 68 to a bracket 69 secured to the bottom of the casing at 70. This armature carries the upwardly extending rod 71 which is provided at its upper end with the ball 72 of insulating material which is adapted to engage the contact plate 44 and move it into a position to be engaged by the notch 49 on the end of the pawl 39, whenever the pawl 67 is attracted by the magnet 65. A bracket 75 is secured to the casing by means of the screws 76 and a spring 73 is adjustably secured to this bracket as at 74 and to armature 67 so that the spring holds the armature normally out of engagement with the solenoids.

I am aware that the structure which I have here shown is susceptible of considerable variation without departing from my invention, and I therefore do not wish to be limited by the specific details of construction set forth in the drawings.

restricted to it. However, the particular embodiment I have here shown is very advantageous and is to be preferred and I desire to claim it specifically, as well as broadly, as indicated by the appended claims.

Having thus described my invention, what I claim as new and desire to secure by Letters Patent, is:

- 10 1. In a device of the class described, the combination of a casing, a post secured to the side wall of said casing, a contact pin adjustably mounted in said post, a contact plate pivotally mounted in said casing so as to move into engagement with said contact pin, an L-shaped pawl pivotally mounted in said casing, a notch in the upper arm of said pawl adapted to engage the top of said contact plate, a normally energized electro-magnet, a pivoted armature for said magnet engaging the lower arm of said pawl, a spring secured to said armature and tending to draw the same away from said magnet, a second electro-magnet, a pivoted armature for said magnet, a spring tending to draw said armature away from the magnet, a push rod carried on the end of said armature, a ball of insulating material secured on the end of said push rod in position to engage the contact plate, all coacting substantially as described for the purpose specified.
- 15 2. In a device of the class described, the combination of a casing, a post secured to the side wall of said casing, a contact pin adjustably mounted in said post, a contact plate pivotally mounted in said casing so as to move into engagement with said contact pin, an L-shaped pawl pivotally mounted in said casing, a notch in the upper arm of said pawl adapted to engage the top of said contact plate, a normally energized electro-magnet, a pivoted armature for said magnet engaging the lower arm of said pawl, a second electro-magnet, a pivoted armature for said magnet, a push rod carried on the end of said armature, a ball of insulating material secured on the end of said push rod in position to engage the contact plate, all coacting substantially as described for the purpose specified.
- 20 3. In a device of the class described, the combination of a casing, a post secured to the side wall of said casing, a contact pin adjustably mounted in said post, a contact plate pivotally mounted in said casing so as to move into engagement with said contact pin, an L-shaped pawl pivotally mounted in said casing, a notch in the upper arm of said pawl adapted to engage the top of said contact plate, a normally energized electro-magnet, a pivoted armature for said magnet engaging the lower arm of said pawl, a second electro-magnet, a pivoted armature for said magnet, a push rod carried on the end of said armature, a ball of insulating material secured on the end of said push rod in position to engage the contact plate, all coacting substantially as described for the purpose specified.
- 25 4. In a device of the class described, the combination of a casing, a contact member, a second contact member mounted so as to move into engagement with the first contact member, a pawl mounted so as to engage said contact member and hold it out of engagement with the first contact member, a normally energized electro-magnet, a pivoted armature for said magnet engaging said pawl and adapted when the magnet is deenergized to lift said pawl out of engagement with the contact member, a second electro-magnet, and means controlled by the energizing of said magnet for moving said second contact member out of engagement with the first contact member, all coacting substantially as described for the purpose specified.
- 30 5. In a device of the class described, the combination of a casing, a fixed contact member, a movable contact member adapted to move into engagement with said fixed contact member, a pawl engaging said movable member and holding it out of engagement with said fixed member, a normally energized electro-magnet, and means controlled by the deenergizing of said magnet for moving said pawl out of engagement with said movable contact member, a second electro-magnet, means controlled by the energizing of said magnet for moving said movable contact member out of engagement with the fixed member, all coacting substantially as described for the purpose specified.

In witness whereof, I have hereunto set my hand and seal in the presence of two witnesses.

HOMER A. PARRISH. [L. S.]
